UNITED STATES PATENT OFFICE.

JOHN B. DAVIS, OF DAYTON, OHIO, ASSIGNOR TO THE AMERICAN OIL PUMP AND TANK COMPANY, OF DAYTON, OHIO, A CORPORATION OF OHIO.

OIL-PUMP.

1,000,965.

Specification of Letters Patent. Patented Aug. 15, 1911.

Application filed April 6, 1911. Serial No. 619,236.

To all whom it may concern:

Be it known that I, JOHN B. DAVIS, a citizen of the United States, residing at Dayton, in the county of Montgomery and State of Ohio, have invented certain new and useful Improvements in Oil-Pumps; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to new and useful improvements in self-measuring oil pumps.

The objects of the invention are, to provide an improved form of continuous or total counter which registers the total amount 20 of oil delivered by the pump, to provide an improved form of supplemental counter which indicates the amount of oil that may be delivered to a single container, and to provide an improved form of stop for limiting the action of the pump when discharging fractional quantities of oil.

In the various municipalities throughout the country, the laws relating to weights and measures provide for a sealer whose 30 duties are to inspect measuring devices as well as scales, and if found to be correct, to place their stamp or seal upon them. In the case of self-measuring oil pumps, the indicating stops which control the discharge 35 of the various quantities of oil are sealed after being adjusted to the proper positions. Heretofore it has been necessary to place a seal on each individual stop, owing to stops being controlled, in their locked positions, 40 by individual means such as set screws. The present invention obviates this and renders it possible to employ a single seal for all the stops, as will hereinafter more fully appear.

45 Referring to the accompanying drawings, Figure 1 is a front elevation of a self-measuring oil pump with my improvements applied thereto, the same being partially in section; Fig. 2 is a side elevation of the 50 same partially in section; Fig. 3 is a front elevation of the total counter; Fig. 4 is a top plan view of the same; Fig. 5 is a section on the line *a a* of Fig. 2 and *b b* of Fig. 6, showing a detail view of the supplemental counter. Fig. 6 is a section on the line *c c*

of Fig. 5, Fig. 7 is a detail view of the stop mechanism for limiting the movement of the pump when dispensing fractional quantities; and Fig. 8 is a section on the line *d d* of Fig. 7.

60

Throughout the specification and drawings, similar reference characters indicate corresponding parts.

Referring more particularly to the drawings, 1 represents a cylinder mounted upon a lower chambered member 2 supported upon a base or pedestal 3. Mounted upon the upper end of the said cylinder is an upper chambered member 4 which is provided with an outlet orifice 5, and which is connected with the lower chambered member 2 by side tubes 6. The lower chambered member is provided with a suction inlet 7 and mounted within the chambers of the upper and lower members 2 and 4 are valves 8 which control the liquid passing therethrough. The liquid is pumped through the cylinder 1, members 2 and 4, and tubes 6 by a piston 9 mounted within the cylinder 1 and attached to the lower end of a piston rod 10. The piston rod 10 extends upwardly through the upper member 4 and a gland 11, and on its upper end it is provided with a rack 12 guided by the upper portion of a frame 13. The frame 13 is attached to the upper chambered member 4. In mesh with the rack 12 is a pinion 14 mounted on a shaft 15 journaled in the frame 13, Fig. 1. Also mounted on the shaft 15 is a gear 16 in mesh with a pinion 17 driven by a crank 18 having bearings in the frame 13. When the crank 18 is oscillated, the piston 9 is reciprocated, and the oil or other liquid is drawn in through the inlet 7 and discharged through the outlet 5. It is contemplated that the internal diameter of the cylinder 1 and the stroke of the piston is such that each upward and downward movement of the piston will discharge a definite quantity of oil from the pump; for example, one gallon. In the construction shown in the drawings, the stroke of the piston is such, that the amount of liquid discharged from below the piston will be sufficient to compensate for the shortage of 95 that discharged from above the piston, due to the displacement by the piston rod, to secure the full discharge of the definite quantity by both strokes.

The above described mechanism consti-

tutes one form of self-measuring oil pump, the individual features of which form no part of the present invention.

To count the number of up and down strokes of the piston to register the total amount of oil discharged by the pump, the following counter is provided. Mounted within a housing 20 on the frame 13 is a counter consisting of wheels 21 progressively actuated by transfer wheels 22. The wheels 21 and 22 are pivotally mounted on a frame 23, and the unit wheel 21^a is provided with a gear 24 in mesh with a worm gear 25. The worm 25 is mounted on a shaft 15 which carries a gear 27 in mesh with a gear 28 which is in turn in mesh with a gear 29. The gears 28 and 29 are mounted on a plate 30 attached to the frame 13 and the gear 29 carries a ratchet wheel 31 engaged by a spring-controlled pawl 32 carried by an arm 33. The arm 33 is mounted on a stub shaft 34 attached to the shaft 15 on which the pinion 14 is mounted. The arrangement of the ratchet and gearing is such, that upon each oscillation of the crank 18, rack 12 and shaft 15, the unit wheel 21^a will be rotated one tenth of a revolution, thereby registering the number of definite quantities of oil discharged from the pump. The wheels 21 are provided with numerals which may be read through a sight opening in a plate 19, and which are separated by intervening lines or dashes. The number of gallons of oil may therefore be read directly from the counter, and the fractional quantities estimated from the position of the intermediate dashes.

A counter thus constructed is simple in construction and efficient in operation, and as the action is positive, the possibility of errors is entirely eliminated.

To ascertain the amount of oil that may be discharged into a single container, a supplemental counter that may be easily reset to zero is provided as follows. Mounted on the frame 13 is a circular housing 35 provided with a pin 36 on which a counting wheel 37 may rotate. The wheel 37 is provided with a flange 38 having numerical characters which may be viewed through a sight opening 39 in the housing 35. The wheel 37 is also provided with a marginal flange 40 by means of which said counting wheel may be manually rotated in either direction to reset to zero. The central portion of the wheel 37 is provided with a ratchet 41 adapted to be engaged by a pawl 42 mounted on an arm 43 pivoted on the pin 36. The arm 43 extends out through an opening 44 in the housing 35, and the shape of the pawl 42 is such, that when the arm 43 is in a normal position, said pawl will engage the edge of the housing 35, thereby elevating the pawl 42 and allowing the counting wheel 37 to be freely and manually

rotated in either direction. The outer end of the arm 43 is provided with a resilient portion 46, such as a closed coil spring which is in a position to be engaged by a pin 45 on the rack 12 when said rack is reciprocated. The movement of the arm 43 is limited by the opening 44, and an extended movement of the rack 12 will be compensated for by the resilient portion 46 of the arm, which prevents the arm 43 acting as a stop for the rack and thus prevents strains being thrown on the counter. It will be seen that the supplemental counter is simple in construction and may be easily set to zero, as the counting wheel may be rotated in either direction. This is due to the fact that the actuating pawl is free from the ratchet when the various members are in a normal position.

To limit the upward movement of the rack 12 to various predetermined distances, thereby allowing the pump to discharge fractional quantities of oil at each oscillation of the crank, the following means are provided. Mounted in the frame 13 and lying parallel with the rack 12, is a rod 50 provided with threads preferably of small pitch. Mounted on the rod 50 and provided with threads agreeing with the threads of the rod, is a plurality of stop members 51 adapted to be rotated thereon within substantially a circle. The rack 12 is provided at its lower end with a lateral projection 52 adapted to engage any one of the stop members 51 when said stop member is swung to a position in the path of said projection. Each stop member 51 represents a definite quantity or fractional quantity of oil such as gallon, half gallon, quart and pint, and are arranged upon the rod 50 according to their value. When the stop member 51 representing a quart, is swung into the path of the projection 52, the movement of the rack 12 will be limited to one fourth that when the pump is discharging its full capacity or one gallon. The particular construction of the stop members 51 is such that space is provided in which to indicate the quantity of oil pumped when a particular stop arrests any further movement of the piston. The position of the stop members 51 may be adjusted by rotating said members on the rod 50, and after they are set they are locked in their adjusted position by a rod 53 mounted in the frame 13 parallel with the rod 50 and adjacent thereto. The rod 53 is held in position by a screw 54 over which a seal may be placed by the proper official. The placing of the seal of the official sealer of weights and measures is done after the various stops 51 are placed in the positions. It will be obvious that any subsequent removal of the locking rod 53 will require a breaking of this seal and a consequent violation of the

law by the continued operation of the pump after such breaking of the seal. As the upper member 51 represents the full discharging capacity of the pump, and in no case is it necessary to swing or rotate the same out of the path of the projection 52, said upper stop member 51 is provided with an extension 53 which engages the rod 53 and prevents possible rotation of the upper member 51 after it has once been adjusted. As this upper member 51 can never be swung out of the path of the projection 52, the pump can never discharge more than the maximum predetermined quantity of oil. A stop device thus constructed will allow a maximum number of stop members to be used, as each member is actuated independently; and as the screw threads are of fine pitch, the adjustment may be made very accurate. It will also be noted that the threads prevent the possible displacement of the stop members on the rod 50 from the continuous tapping of the projection 52.

Having described my invention, I claim:

1. In a device of the type specified, the combination with a casing of a reciprocating member, a counting wheel rotatable in either direction, and provided with a ratchet, an arm adapted to be actuated by said reciprocating member, a pawl mounted on said arm, said pawl being constructed and arranged to engage an adjacent portion of the casing when said arm is lowered, thereby freeing it from engagement with said ratchet.

2. In a device of the type specified, the combination of a reciprocating member, a counting wheel provided with a ratchet, an arm adapted to be engaged by said reciprocating member, a pawl on said arm adapted to engage said ratchet and to rotate said counting wheel when said arm is actuated by said reciprocating member, said arm having a resilient portion whereby when the counter is fully actuated an extended movement of the reciprocating member will not be communicated to said wheel.

3. In a device of the type specified, the combination of a reciprocating member, a threaded rod parallel with said reciprocating member, a rotatable indicating stop on said threaded rod adapted to be swung into a position to be engaged by said reciprocating member, and to limit the movement of said reciprocating member, and means for preventing a complete rotation of said reciprocating member on said threaded rod.

4. In a device of the type specified, the

combination with a reciprocating member, of a threaded rod parallel with said member, a plurality of swinging stops mounted on said rod, each of which is adapted to be swung into a position to be engaged by said reciprocating member and out of such position, and means for preventing a complete, 65 rotating of said swinging members.

5. In a device of the type specified, the combination with a reciprocating member, of a threaded bar lying parallel with said reciprocating member, a plurality of swinging stops mounted on said bar and adapted to be swung into a position to engage said reciprocating member to limit the movement of the same, and a rod lying parallel with and adjacent to said threaded 75 member and adapted to prevent a complete rotation of said stops.

6. In a self-measuring oil pump, the combination of a cylinder, upper and lower chambered members communicating with said cylinder, exterior valve-controlled pipes providing passages between said upper and lower chambers, a piston within said cylinder having an upwardly extended rod, a reciprocating rack secured to said 85 extended rod, a counting wheel for registering the number of reciprocations of said rack, an arm having a resilient portion, a pawl on said arm adapted to engage and actuate said counting wheel, and a pin on 90 said rack adapted to engage said resilient portion of said arm.

7. In a self-measuring oil pump, the combination of a cylinder, upper and lower chambered members communicating with said cylinder, exterior valve-controlled pipes providing passages between said upper and lower chambers, a piston within said cylinder having an extended rod, a reciprocating rack on said rod, said rack 100 having a stop extension thereon, driving means engaging said rack, a screw-threaded rod mounted parallel with said rack, a series of indicating stops on said screw-threaded rod adapted to be individually moved 105 out of and into engaging positions with the stop on said rack, and a parallel rod adjacent to said screw-threaded rod and controlling the movement of said stops on said screw-threaded rod.

In testimony whereof I affix my signature, in presence of two witnesses.
